Fred L. Mackenzie

UNITED STATES PATENT OFFICE.

FRED L. MACKENZIE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

NAIL.

1,400,756.

Specification of Letters Patent. Patented Dec. 20, 1921.

Original application filed October 14, 1914, Serial No. 866,675. Divided and this application filed September 4, 1917. Serial No. 189,428.

To all whom it may concern:

Be it known that I, FRED L. MACKENZIE, a citizen of the United States, residing at Beverly, in the county of Essex and State 5 of Massachusetts, have invented certain Improvements in Nails, of which the following description, in connection with the accompanying drawings, is a specification, like reference characters on the drawings indicating like parts in the several figures.

This invention relates to fastenings and is illustrated as embodied in fastenings of the type commonly termed "string nails."

String nails are used for the most part 15 in shoe nailing or tacking machines and the ordinary nail string supplied for such machines comprises a series of nails formed in one integral string, usually with the point or end of the shank of one nail connected to 20 some part of the head of the next nail. In use the nail string is carried upon a reel and the nailing machine is provided with means for engaging the head of the nail to be driven, feeding it into the throat of the machine, and severing it from the string. The 25 mechanism of the machine for handling these nails is very simple, and for many purposes it would be desirable to employ string nails if they could be manufactured 30 economically, and could be provided with heads sufficient to prevent their being pulled through the parts which are to be secured together by them.

It is advantageous from the commercial 35 standpoint to form the nails or nail strings from sheet metal, and if the nail is to be used as a permanent fastening, it is important that it have formed thereon a considerable head projecting to one or both sides of 40 the shank in the plane of the strip, since it is obviously not possible without a swaging operation to cause the head to project over the flat sides of the nail shank. A 45 convenient, economical and practical method of manufacturing nail strings comprising such nails is described and claimed in Letters Patent No. 1,241,868, granted Oct. 2, 1917, on my co-pending application Ser. No. 866,675, filed Oct. 14, 1914, of which this 50 application is a division.

An object of the present invention is to provide an improved nail capable of being

manufactured in union with other nails of the same kind in a nail string and having a head of much greater holding power than 55 the ordinary string nail head, and an important feature of the invention resides in a string nail having a hook-shaped head of an improved form.

Figure 1 illustrates a pair of nail strings 60 constituting an embodiment of the invention and illustrating their manufacture from a single strip; and Fig. 2 illustrates a nail as severed from the nail string of Fig. 1.

Each of the nail units of the string shown 65 in the drawing comprises a shank 2 having a straight edge 4, which is the edge of the ribbon or strip of sheet metal from which the nail string is cut, an inclined edge 6 and a head 8, which is of curved hook shape 70 upon its under side, the downwardly projecting barb or point 10 of the head acting to increase considerably the holding power of the head. The curve is found advisable because of practical difficulties in the manufacture of a sharp cornered outline, and the 75 sides of the curve also reinforce the head and keep it from breaking off readily. It will be noticed that the head is "unbalanced," i. e., it extends to one side only of the shank. 80 It is therefore necessary that it drive straight in order to avoid lateral pressure or "draw" on the shank which would loosen it in its hole. In order to obtain this advantage the barb 10 is preferably beveled 85 slightly at 11 upon its outer edge to form a symmetrical point and to compensate somewhat for the tendency of the curved inner edge to turn out the point or draw the head in the driving operation. 90

Having thus described my invention, what I claim as new and desire to secure by Letters Patent of the United States is—

1. A nail formed of sheet metal, having a shank and an unbalanced head lying in 95 the plane of the shank, said head having a depending projection on its under side at its extremity, the projection having a lower surface extending transversely of the nail shank and having faces inclined toward each 100 other in the plane of the shank.

2. A nail having a shank and a head, said head having a depending projection on its underside at a point remote from the shank,

the projection having faces inclined toward each other and both inclined with respect to the shank.

3. A nail having a shank and a head extending in a single direction from the shank, said head having a depending projection on its underside at its extremity, the lower sur-

face of the projection being flattened and extending in a direction substantially at right angles to the shank of the nail. 10

In testimony whereof I have signed my name to this specification.

FRED L. MACKENZIE.
